United States Patent

Des. 238,218
Patented Dec. 30, 1975

238,218

BOOT SOLE

Lyle J. Cohn, Lyndhurst, Ohio, assignor to International Seaway Trading Corporation

Filed Dec. 21, 1973, Ser. No. 427,066

Term of patent 14 years

Int. Cl. D2—04

U.S. Cl. D2—319

Fig. 1

Fig. 2

FIG. 1 is a side elevational view of a boot sole showing my new design, the side opposite being substantially similar thereto; and

FIG. 2 is a bottom plan view thereof.

I claim:

The ornamental design for a boot sole, substantially as shown and described.
